UNITED STATES PATENT OFFICE.

JOHN M. OLIN, VICTOR L. DAVIS, AND JOHN B. SMITH, OF ALTON, ILLINOIS, AS-
SIGNORS TO WESTERN CARTRIDGE COMPANY, OF EAST ALTON, ILLINOIS, A COR-
PORATION OF DELAWARE.

METHOD AND APPARATUS FOR MAKING IGNITER CONNECTIONS FOR DETONATORS.

Application filed December 30, 1922. Serial No. 609,954.

This invention relates to detonators and more particularly to those of the electrically ignited type.

One of the objects of this invention is to provide improved processes and mechanism, whereby the detonators, and more particularly the igniter connections, may be made economically, with accuracy and in order to produce an article which will be reliable and simple.

Another object of this invention is to provide an improved detonator and more particular improved igniter connections therefor.

Further objects will appear from the detail description taken in connection with the accompanying drawings, in which:

Figure 1 is a detail perspective view, partly in section, illustrating the process for forming the plugs on the connections;

Figure 2 is a similar view still further illustrating this process;

Figure 3 is a similar view illustrating the process of trimming and stripping the detonator connection terminals;

Figure 4 is a similar view illustrating the forming of the detonator connection terminals in order to receive the filament;

Figure 5 is a detail perspective view illustrating the attaching of the filament to the terminals and the plating of this filament and terminals;

Figure 6 is a similar view illustrating the coiling of the connections;

Figure 7 is a detail section illustrating the sealing of the detonator connection terminals in the shell;

Figure 8 is a section, somewhat enlarged, of the detonator;

Figure 9 is a perspective view showing the complete package;

Figure 10 is a side elevation showing the mechanisms for forming the plugs on the detonator connections and for trimming and stripping the connections;

Figure 11 is a detail of the guiding rollers as shown by section taken on line 11-11, Figure 10;

Figures 12 and 13 are details of the holder;

Figure 14 is a detail of the plug forming mechanism;

Figure 15 is a section on line 15-15, Figure 14;

Figure 16 is a detail showing a series of plugs formed on the connections.

Referring to the accompanying drawing, and more particularly to Figures 7, 8 and 9, the detonator, as shown, comprises a shell 1 which may be of drawn metal and has charge components 2 and 3 of any improved composition and arrangement, and the upper end of this shell is beaded as shown at 4. In this shell are arranged the terminals 5 of the connections 6 which pass through a plug 7 formed on the connections and of a suitable composition, a satisfactory one being a mixture of sulphur and graphite. The connections are insulated wires which are stripped from where they project through the plug and these connections are formed, as hereinafter described, to receive the filament 8. This filament may be of any suitable resistance wire, a satisfactory one being of a composition of nickel, iron and copper. In order, however, to secure this filament to the terminals they are dipped in solder which also serves to coat or plate the filament as well as the connections, in order to protect them against deterioration when in the shell. The plug and its terminals are secured within the shell by additional plugs 9 and 10 of sulphur and pitch, which serve to seal and cap the shell and the terminals therein. These plug components are poured into the shell as hereinafter described so as to flow around the connections, and it will be noted that the composition flows into the bead 4 so as to firmly secure and lock the parts together.

The connections 6 are coiled on a tube 11 which may be of paper or any other suitable material, and the end of this tube is slotted as shown at 12, Figure 9, to receive the end strands while the connections are coiled on the tube back and forth. The strands leading to the shell also pass through the slot 12 and sufficient length is left so as to permit insertion of the shell into the tube and within the coiled connections wound therearound.

Having thus described in a general way the construction, arrangement and formation of the detonator and its connections,

we will proceed with the detail description of the several subprocesses and the mechanisms for performing the same.

5 Casting the plug on the connections.

Referring to Figures 1, 2, and 10 to 16 inclusive, 15 designates a mold body which has a series of mold cavities 16 therein, the bottoms of which are formed by plungers or ejectors 17. The top of the mold body is closed by plates 18 and 19 and a blade 20; the plates 18 and 19 are arranged to slide on the mold body 15 while the blade 20 is secured to the plate 19 so as to move therewith. The plate 19 and the blade 20 are recessed as shown to form a gate 21 and runners 22 leading from the gate to the several mold cavities.

20 The mold body is supported by brackets 23 on the top 24 of a frame 25 and the plates 18 and 19 are pivoted at 26 on the mold body and provided with handles 27 to effect their manipulation. A headed stop 28 is mounted on the mold body and cooperates with recesses on the plates 18 and 19 in order to properly position the meeting faces of these plates medially of the line of mold cavities in the mold body. The plungers 17 are mounted on a cross-head 29, moving on guides 30 extending from the mold body and connected with a lever 31, which has an extension 32 connected by a link 33 with a treadle 34 and engaged by a spring 35, which tends to normally hold the plungers in depressed position with the parts 36 of the cross-head in engagement with the base 24, in order to properly position the plungers in the mold cavities.

40 The plungers are each perforated to form guides 37 for the connections 6 below the mold cavities, while the plates 18 and the blade 20 are also recessed as shown at 38 to provide guides for these connections above the mold cavities. The connections, therefore, pass through the mold cavities and are positioned therein by the guides, while the plunger 17 at the bottom and the plates 18 and 19 and the blade 20 at the top, definitely fix the volume of these molds.

50 The connections 6 are arranged on suitable reels 39 mounted on a frame 40 below the mold body and suitably arranged on the frame, to supply pairs of connections to the mold cavities and the guides leading to and therefrom. In order to guide these connections, a pair of guiding rollers 41 are provided which have formed therein annular recesses 42 providing guide-ways for pairs 60 of connections, in order to guide each pair to its proper mold cavity. The connections leaving the mold pass through guide rolls 43 which are grooved similar to the rolls 41 and are mounted on brackets 44 on the table 24, the upper roll 43 being removable

from the brackets to permit placement of the connections.

The connections, continuing, pass through the jaws 45 and 46 of a clamp mounted on the table 24 and provided with clamping nuts 47. This serves to secure the connections in place and against shifting.

Assuming that a series of pairs of connections have been positioned in the mold cavities as shown in Figures 1, 10 and 15, the composition is poured into these cavities through the gate 21 and runners 22 so as to flow into these cavities and around the connections. The plate 19 and its attached blade 20 are then moved to the right, thereby causing the blade 20 to shear the sprues from the composition formed in the cavities. Upon still further movement of the plate 19 and also movement of the plate 18 to the left, the mold cavities are opened. By then depressing the treadle 34 the plungers 17 are raised so as to eject the plugs 7 formed on the connections. Each pair of connections is thus provided with a plug formed thereon and joining these connections, and since the plug is formed in a smooth faced mold, it will have a smooth exterior as well as a definite length and diameter. This smoothness of the plug can moreover be enhanced by preliminarily pressing on the treadle 34 before the plates 18 and 19 have been shifted and after the composition has partially cooled in the runners 22, as this serves to condense the composition and form the plugs more accurately to shape.

55 After the mold has been opened by shifting of the plates 18 and 19, the connections are shifted upwardly and along the table, past the rollers 43 (the top one of which can be removed), past the clamp 45-46 (the top 46 of which has been removed) and past the cutting and trimming mechanism shown to the left of the clamp 45-46. The length of the connection is thereby measured. The clamp 45-46 is now again closed, the rollers 43 replaced, the mold cavities closed and another set of plugs is formed on the connections. This procedure is continued so that a series of plugs are formed on a series 60 of sets of connections.

Cutting and stripping the connections.

Referring to Figures 3 and 10, mounted on the table 24 is a base 48 which carries a stationary cutter 49, a gage 50 and a bracket 51 which has an opening at 52 to permit entrance of the wires. The cutter 49 has a cutting face 53 on the right and a series of notched cutting edges 54 on the left. Pivoted at 55 on the bracket 51 are a pair of connected blades 56 and 57 arranged for cooperation with the cutting edges 53 and 54. The blade 57 is notched and sharpened to correspond to the sharpened notches 54 on the cutter 49. The gage

50 has a series of recesses 58 adapted to receive the plugs 7 on the connections 6, while these connections are received by the notches in the cutter 49, and the blade 57 and the 5 left face of the cutter 49 provides a stop for these plugs.

The connected blades 56 and 57 are arranged to be moved down to cooperate with the cutter 49, by a treadle 59 connected by a 10 link 60 with the free ends of the connected blades, while these blades are returned by a spring 61 on the cutter 49. The connection between the link and the connected blades is through the medium of a hook 62 so that 15 these connected blades may be swung out of the way.

After the plugs 7 have been cast on the connections, these connections are strung through the opening 52 so as to position the 20 plugs 7 in the notches 58 on the gage 50 and with the plugs against the cutter 49. The connections and the plugs thereon are at this time held between a clamping element 45 fixed on the base 48 and a cooperating 25 movable element 46. This will position the connections in the notches 54 of the cutter 49 and with the right face of the plug a predetermined distance from the cutting edge 53. By now moving the connected cutter blades 56 and 57 towards the cutter 49, the blade 56 will operate to sever the connections a predetermined distance from the 30 plugs. The cooperating edges of the cutter 49 and the blade 57 will, however, simply 35 cut through the insulation of the connections without cutting into the metallic conductors enclosed by the insulation. While the blade 57 is still held in depressed position the connections 6 are moved to the left, thereby 40 stripping the insulation from the connections projecting beyond the plug, as shown in Figure 4.

Formation of the terminals.

45 Referring to Figure 4, 63 is a block which is provided with a pair of passages 64 forming supporting guides for the terminals 5, and with a recess 65 forming a support for the plug 7 on the connections 6. The bottom of the block is provided with a V-shaped groove 66 into which the terminals project with the apex of the groove passing medially through the aligned terminals. Co- 50 operating with this groove, which forms a die, is a V-shaped punch 67. Accordingly when the terminals projecting from beyond the plug are positioned as shown, operation of the punch will cause the same to cut aligned V-shaped notches in these terminals 55 as shown in Figure 6.

The filament attaching and plating.

Referring to Figure 5, 73 designates a solder pot, which is provided with molten 60 solder, and on one side of this pot is sup-

ported a reel 74 while on the other side are the stationary and movable parts 75 and 76, respectively, of a combined cutter and clamp, whereby a strand of the filament wire 77 may be stretched across the pot and 70 clamped on one side thereof.

Assuming the filament wire to be stretched over the solder and clamped as shown in Figure 5, the terminals 5 projecting from the plug 7 are placed in aligned relation, with 75 the notches in the terminals taking over the wire. The plug and terminals are now moved down, carrying the wire with them into the solder and thereby not only causing the wire to be soldered to the terminals, but also coating the wire as well as the terminals with a plating of the solder. It will be understood, of course, that the terminals are first dipped in a suitable flux before 80 immersion into the solder; the solder can be of any suitable composition, such as a lead tin alloy. After the wire has been soldered to the terminals, the plug and terminals are moved to the right, as the combined cutter and clamp 75-76 is opened, 85 until the wire to the left of the terminals is in cooperation with the cutter and clamp. The latter is then closed, thereby cutting off the wire connected to the terminals and also 90 clamping the wire in stretched condition 95 across the solder pot.

Coiling the connections.

Referring to Figure 6, 94 designates a mandrel which is adapted to receive the tube 11. This mandrel is slotted as shown at 95 to correspond with the slot 12 in the end of the tube. Fixed to the mandrel is a face-plate 96 which is recessed as shown at 97 to receive and cover the end of the tube. 100

In the operation of winding the connections on the tube, the terminal end of the strand connected to the plug 7 is passed through the slots 12 and 95 in the tube and mandrel, thereby serving to connect the tube with the mandrel. Upon rotation of the mandrel, the connections are coiled on the tube and the free ends of the strands are then again passed through the slots 12 and 95. The whole can then be removed 110 from the mandrel, and after the shell is attached, this shell can be inserted in the tube as shown in Figure 9, while the free ends of the connections can be wrapped around the coil. It will be noted that in view of the fact that the end of the tube has been covered by its insertion in the mandrel, the connections can be coiled close to the mandrel, at the same time leaving part of the tube uncovered, so as to present a neat package 115 as well as preventing uncoiling of the connections. 120

Capping or sealing the shell.

Referring to Figure 7, after the terminal 130

connections have been completed, the plug is inserted into the shell 1, and the plug components 9 and 10 of sulphur and pitch are poured into the shell and around the connections so as to form a seal and a lock as previously described. In order to position the terminals and filament properly in the shell and with respect to the charge, the connections 6 themselves may be utilized 10 as such positioning means. Accordingly, the shell is placed in a recess 103 formed in a suitable support 104, the top of the recess being preferably enlarged as shown at 105, so that the bead 4 will strike against 15 the shoulder formed at the bottom of the enlargement. This base is also provided with a flange 106 over which the connections take in order to properly position the plug and its terminals within the shell. The base 20 104 may be provided with a table 107 on which the coiled connections can rest during the filling operation.

The filling component may be in a pair of tanks, one of which is shown at 108 and 25 is provided with a spout 109 and a measuring device 110 having pockets 111 for measuring predetermined quantities of the sealing component into the shell. It will be understood, of course, that the tank is heated 30 which may be accomplished in any suitable manner, as by electrical heating coils (not shown). After the shell has been sealed on the connections, this shell is inserted into the tube 11 as shown in Figure 9. A drip receiver 112 is provided which moves to positions below and clear of the spouts 109.

Resumé of operations.

The several operations may be briefly 40 summarized as follows, referring to Figures 1 to 9 inclusive.

The connections are positioned in the molds by the guides provided and the composition is poured into the mold cavities 45 through the gate and runners provided. The sprues are then sheared off, the mold cavities opened and the plugs formed on the connections ejected therefrom. The connections are now drawn through the molds and the 50 plugs placed on the gages of the cutting and stripping mechanism, which will not only measure off the loose strands of the connections, but also properly position the plugs with respect to the cutters. The connections are then severed and the terminals stripped as shown in Figure 3. The terminals and plug are now placed in the forming mechanism, the punch of which operates to form alined V-shaped notches in the 55 terminals a predetermined distance from the plug, the terminals being properly alined with reference to the forming tool, as shown in Figure 4. The terminal is now placed over the filament wire, which is stretched 60 over the solder with one end of the filament

wire fastened to hold it stretched; by now moving down on the terminals, the notches of which take over the wire, the wire as well as the terminals are dipped into the solder to not only fasten the filament wire 70 to the terminals, but also to plate this filament and the terminals, as shown in Figure 5. The connections are now coiled or spooled as shown in Figure 6, leaving the terminal ends as well as the free ends of the connections securely fastened. The plug is now placed in the shell, being properly positioned therein as shown in Figure 7, and measured quantities of the sealing components are poured into the shell and around 75 the connections to provide a seal and a lock. The shell secured and sealed on the connections is now inserted into the tube and the connections coiled thereon as shown in Figure 9. 85

It will, therefore, be seen that this invention accomplishes its objects. By the process and mechanism described the detonator can be made with a minimum of expense; however, the operations are so performed that each operation will effectively secure its objects and accurately prepare the subject matter for the succeeding operation. A detonator is provided which is of improved construction and which is not subject to deteriorating while it is convenient for use as well as shipment. 95

It is obvious that various changes may be made in details without departing from the spirit of this invention; it is, therefore, to be understood that this invention is not to be limited to the specific details shown and described. 100

Having thus described the invention, what is claimed is: 105

1. In the art of making detonators, the process comprising, casting a series of plugs at spaced points on an igniter connection. 110
2. In the art of making detonators, the process comprising, positioning the igniter connection in a mold, and pouring the composition in the mold and around the connection in order to form a plug thereon. 115
3. In the art of making detonators, the process comprising, positioning the igniter connection in a mold, pouring the composition in the mold and around the connection, and shearing the sprue from the plug formed on the connection. 120

4. In the art of making detonators, the process comprising, positioning the igniter connection in a mold, pouring the composition in the mold and around the connection, and ejecting the plug formed on the connection from the mold. 125

5. In the art of making detonators, the process comprising, positioning the igniter connection in a mold, pouring the composition in the mold and around the connection, shearing the sprue from the plug formed 130

- on the connection, and ejecting the plug from the mold. 6. In the art of making detonators, the process comprising, passing the igniter connection through a mold, and casting the composition in the mold and around the connection in order to form a plug thereon. 7. In the art of making detonators, the process comprising, passing the igniter connections through a mold in stages, and casting a plug on the connection at each stage. 8. In the art of making detonators, the process comprising, passing the igniter connection through a mold in stages and at each stage casting a plug on the connection, and sharing the sprue from the plug. 9. In the art of making detonators, the process comprising, passing the igniter connection through a mold in stages and at each stage casting a plug on the connection, and ejecting the plug from the mold. 10 In the art of making detonators, the process comprising, passing the igniter connection through a mold in stages and at each stage casting a plug on the connection, shearing the sprue from the plug and ejecting the plug from the mold. 11. In the art of making detonators, the process comprising, positioning a series of igniter connections in a mold, and simultaneously pouring the composition in the mold and around the connections in order to form plugs thereon. 12. In the art of making detonators, the process comprising, positioning a series of igniter connections in a mold, simultaneously pouring the composition in the mold and around the connections, and shearing the sprue from the plugs formed on the connections. 13. In the art of making detonators, the process comprising, positioning a series of igniter connections in a mold, simultaneously pouring the composition in the mold and around the connections, and ejecting the plugs formed on the connections. 14. In the art of making detonators, the process comprising, positioning a series of igniter connections in a mold, simultaneously pouring the composition in the mold and around the connections, shearing the sprue from the plugs formed on the connections, and ejecting the plugs. 15. In the art of making detonators, the process comprising, passing a series of igniter connections through a mold in stages, and at each stage, simultaneously casting plugs on the connections, and shearing the sprue from the plugs. 16. In the art of making detonators, the process comprising, passing a series of igniter connections through a mold in stages, and at each stage, simultaneously casting plugs on the connections, and shearing the sprue from the plugs. 17. In the art of making detonators, the process comprising, passing a series of igniter connections through a mold in stages, and at each stage, simultaneously casting plugs on the connections, and ejecting the plugs. 18. In the art of making detonators, the process comprising, passing a series of igniter connections through a mold in stages, and at each stage, simultaneously casting plugs on the connections, shearing the sprue from the plugs, and ejecting the plugs. 19. In the art of making detonators, the process comprising, forming a plug on the igniter connection, and cutting the connection adjacent the plug. 20. In the art of making detonators, the process comprising, forming a series of plugs on and spaced along the igniter connection, and cutting the connection adjacent the plugs. 21. In the art of making detonators, the process comprising, forming a plug on the igniter connection, and stripping the connection adjacent the plug. 22. In the art of making detonators, the process comprising, forming a series of plugs on and spaced along the igniter connection, cutting the connection adjacent the plugs, and stripping the connection adjacent the plugs. 23. In the art of making detonators, the process comprising, forming a plug on the igniter connections, and forming the ends of the igniter connections. 24. In the art of making detonators, the process comprising, stripping the igniter connections, and forming the ends of the igniter connections. 25. In the art of making detonators, the process comprising, forming a plug on the igniter connections, stripping the igniter connections adjacent the plug, and forming the ends of the igniter connections. 26. In the art of making detonators, the process comprising, forming a plug on the igniter connections, and attaching a filament to the terminals of the connections projecting through the plug. 27. In the art of making detonators, the process comprising, forming a plug on the igniter connections, stripping the connections adjacent the plug, and attaching a filament to the stripped terminals. 28. In the art of making detonators, the process comprising, forming a plug on the igniter connections, stripping the connections adjacent the plug, forming the stripped terminals, and attaching a filament to the formed terminals. 29. In the art of making detonators, the process comprising, forming a plug on the igniter connections, forming the terminals of the connections projecting through the plug, and attaching a filament to the terminals.

30. In the art of making detonators, the process comprising, stripping the igniter connections, and attaching a filament to the stripped ends. 50
5. 31. In the art of making detonators, the process comprising, stripping the igniter connections, forming the stripped ends, and attaching a filament to the formed ends. 55
10. 32. In the art of making detonators, the process comprising, forming the terminals of the igniter connections, and attaching a filament to the formed ends. 60
15. 33. In the art of making detonators, the process comprising, forming a plug on the igniter connections, attaching a filament to the projecting terminals, and inserting the plug and its attached terminals and filament into the shell. 65
20. 34. In the art of making detonators, the process comprising, forming a plug on the igniter connections, attaching a filament to the projecting terminals, inserting the plug and its attached terminals and filament into the shell, and sealing the plug in the shell. 70
25. 35. In the art of making detonators, the process comprising, forming a plug on the igniter connections, attaching a filament to the projecting terminals, coiling the free ends of the connections, and inserting the plug and its attached terminals and filament into the shell. 75
30. 36. In a machine of the class described, a mold having a cavity, guides for positioning the connection in said cavity, a gate through which the composition is poured in order to form a plug on said connection, and an element adapted to shear the plug from the sprue. 80
40. 37. In a machine of the class described, a mold having a cavity, guides for positioning the connection in said cavity, adapted for casting a plug on said connection, and an element for ejecting the plug from the mold. 85
45. 38. In a machine of the class described, a mold having a series of mold cavities, guides for positioning a series of connections in said cavities, a gate through which the composition is poured in order to form plugs 90
- on said connections, and elements for ejecting the plugs from the mold. 50
39. In a machine of the class described, a mold having a cavity, guides for positioning the connection in said cavity, a gate through which the composition is poured in order to form a plug on said connection, an element adapted to shear the plug from the sprue, and an element for ejecting the plug from the mold. 55
40. In a machine of the class described, a mold having a cavity, guides for positioning the connection in said cavity, adapted for casting a plug on said connection, and means adapted upon opening of the mold to permit removal of the plug and repositioning of another part of the connection therein. 60
41. In a machine of the class described, a mold having a cavity, guides for positioning the connection in said cavity, a gate through which the composition is poured in order to form a plug on said connection, an element adapted to shear the plug from the sprue, and means adapted upon opening of the mold to permit removal of the plug and repositioning of another part of the connection therein. 70
42. In a machine of the class described, a mold having a cavity, guides for positioning the connection in said cavity, adapted for casting a plug on said connection, and a reel positioned beyond the mold and from which the connection passes to said guides. 80
43. In a machine of the class described, a mold having a series of mold cavities, guides for positioning a series of connections in said cavities, a gate through which the composition is poured in order to form plugs on said connections, and a series of reels positioned beyond the mold and from which the connections pass to said guides. 85
